Patented Dec. 10, 1974

233,889

URINAL FOR PORTABLE TOILET BUILDING

Phillip R. Juaire, Minneapolis, Minn., assignor to
Satellite Industries, Inc., Minneapolis, Minn.

Filed Feb. 5, 1973, Ser. No. 329,603

Term of patent 14 years

Int. Cl. D23—02

U.S. Cl. D23—68

FIG. 1 is a front elevational view of a urinal for a portable toilet building embodying my design;

FIG. 2 is a rear elevational view thereof;

FIG. 3 is a left side elevational view thereof;

FIG. 4 is a right side elevational view thereof;

FIG. 5 is a plan view thereof; and

FIG. 6 is a bottom view thereof.

I claim:

The ornamental design for a urinal for portable toilet building, substantially as shown.
